[57] CLAIM

The ornamental design for a battery, as shown and described.

DESCRIPTION

FIG. 1 is a front and one side perspective view of the battery showing our new design with the handle shown in the closed position;

FIG. 2 is a front and one side perspective view thereof with the handle shown in the open position and the protective covers removed from both sets of the terminals;

FIG. 3 is a top plan view thereof with the protective covers removed from both sets of the terminal;

FIG. 4 is a side elevational view thereof, the opposite side being a mirror image;

FIG. 5 is a rear elevational view thereof; and

FIG. 6 is a bottom plan view thereof.

FIG. 1

FIG. 2

FIG. 3

FIG. 4

FIG. 5

FIG. 6
